UNITED STATES PATENT OFFICE.

CHARLES EDWIN HOLLAND, OF NEW YORK, N. Y.

DESIGN FOR A SKYLIGHT CAP OR COVER.

SPECIFICATION forming part of Design No. 34,283, dated March 26, 1901.

Application filed January 25, 1901. Serial No. 44,763. Term of patent 3½ years.

To all whom it may concern:

Be it known that I, CHARLES EDWIN HOLLAND, a citizen of the United States, and a resident of 245 West One Hundred and Sixteenth street, New York, in the county of New York and State of New York, have invented a certain new and useful Design for Skylight Caps or Covers, of which the following is a specification.

10 My new and original design for skylight construction is shown in the accompanying drawings, in which—

Figure 1 is a side view of the cap or cover, and Fig. 2 an end view of the same.

15 The cap or cover, which spans the joined or abutting edges of the glass plates forming the roof, is composed of a strip of metal bent along a central line, so that the two bent sides are A-shaped in cross-section, as at 3, 20 the body of the sheet being further bent inwardly at 4, so that their lower ends approach

each other, making a diamond-shaped cross-section, as shown. The edges constituting the base are convolute in form or S-shaped, as shown at 5, the convolute portions extending outwardly on each side of the diamond-shaped formation. ²⁵

The essential feature of the design is the diamond-shaped formation of the body in cross-section, with a convolute base on each side. ³⁰

What I claim as new is—

The design for a skylight cap or cover, substantially as shown and described.

Signed at New York, in the county of New York and State of New York, this 23d day of November, A. D. 1900.

CHARLES EDWIN HOLLAND.
